CLAIM

What is claimed is the ornamental design for a miniature bottle tray, as shown and described.

DESCRIPTION

FIG. 1 is a perspective view of a miniature bottle tray showing a new design;

FIG. 2 is a top view of the miniature bottle tray of FIG. 1; FIG. 3 is a bottom view of the miniature bottle tray of FIG. 1;

FIG. 4 is a side view of the miniature bottle tray of FIG. 1; and,

FIG. 5 is a front of the miniature bottle tray of FIG. 1. The components of the display shown in broken lines illustrate portions of the miniature bottle tray that form no part of the claimed design.
